DESK ORNAMENT

Herbert D. Campbell, Phoenix, Ariz.

Application December 15, 1949, Serial No. 6,630

Term of patent 7 years

(Cl. D29—23)

To all whom it may concern:

Be it known that I, Herbert D. Campbell, a citizen of the United States, residing at 5525 Van Buren, Phoenix, county of Maricopa, and State of Arizona, have invented a new, original, and ornamental Design for a Desk Ornament, of which the following is a specification, reference being had to the accompanying drawing forming part thereof.

I claim:

The ornamental design for a desk ornament, as shown.

HERBERT D. CAMPBELL.
